UNITED STATES PATENT OFFICE.

JOHN L. CREVELING, OF NEW YORK, N. Y., ASSIGNOR TO SAFETY CAR HEATING AND LIGHTING COMPANY, A CORPORATION OF NEW JERSEY.

ELECTRIC REGULATION.

1,113,199.

Specification of Letters Patent.

Patented Oct. 13, 1914.

Application filed October 11, 1910. Serial No. 586,481.

To all whom it may concern:

Be it known that I, JOHN L. CREVELING, a resident of New York, in the county and State of New York, have invented certain new and useful Improvements in Electric Regulation, as set forth in the annexed specification and drawing, forming a part thereof.

My invention pertains to that class of electrical regulation wherein it is desired to automatically govern a dynamo or generator in a predetermined manner.

My invention has for its particular object to provide means whereby a dynamo or generator may be automatically governed to produce certain given results throughout widely varying conditions.

A further object of my invention is to provide means whereby a dynamo driven at variable speeds may be automatically regulated to properly charge a storage battery.

As my invention is particularly applicable to systems of electrical distribution wherein a dynamo driven at varying speeds is used to charge storage batteries and operate lamps or other translating devices, it will be described in reference to such a system.

The drawing is a diagrammatic representation of one type of such system embodying the essentials of my invention.

In the drawing 1 represents a dynamo or generator provided with a field winding 2, having in series therewith a means for controlling the field magnetization, in this instance illustrated as the carbon pile 3.

4 represents a lever normally drawn upwardly by the adjustable spring 5, in such manner as to compress carbon pile 3 and reduce the resistance thereof.

6 represents a core of iron or other magnetic material attached to the lever 4 so that the motion of the core 6 is imparted by the lever 4 to carbon pile 3. The positive terminal of the generator is carried as by lead 7 to the positive side of the storage battery 8 and lamps or other translating devices indicated by 9. The negative side of the lamps, or other translating devices, and the storage battery, are connected with the main 10 which is carried through the winding 11 to the negative brush of the generator 1.

12 is a solenoid so arranged that when energized, it will tend to draw the core 6 in a downward direction. One end of the solenoid 12 is connected as by wire 13 with the carbon pile 14, the opposite end of which is

connected as by wire 15 with the lead 7. The other end of the solenoid 12 is connected with lead 10 as by wire 16.

17 represents a lever controlling the pressure upon carbon pile 14 and normally drawn in an upward direction as by the adjustable spring 18, and having its limit of motion in this direction governed as by adjustable screw 19. The lever 17 is provided with a core of iron or other magnetic material, indicated at 20 in such relation to the solenoid 11 that excitation of the same tends to draw the core 20 in a downward direction and thus compress the carbon pile 14.

21 represents a lever controlling the pressure upon the carbon pile 14, and normally drawn in an upward direction as by adjustable spring 22, the upward movement of said lever being limited by adjustable screw 23. The lever 21 carries the core 24, of iron or other magnetic material surrounded by the solenoid 25 in shunt across the battery as indicated, and so disposed that when energized, it will tend to cause the core 24 to be drawn downwardly, and the pressure upon the carbon pile to be increased.

The operation of my invention is substantially as follows: If the generator be running at such speed as to have an electro-motive force sufficient to cause it to supply its normal maximum output, current will flow through the field 2 in a well-known manner and the generator may be governed by varying the pressure upon the carbon pile 3. Current will also flow to the lamps and storage battery through lead 7, and return through lead 10 and winding 11 to the generator. Current will also flow from the lead 7 through wire 15, carbon pile 14, wire 13, solenoid 12 and wire 16 to the lead 10, and this current will depend upon the amount of resistance in the carbon pile 14. I so adjust the spring 18 that when the normal current output of the generator is reached, any further increase in current will cause the solenoid 11 to draw down core 20 and depress the lever 17 in such manner as to compress the carbon pile 14 and increase the current flowing in the winding 12 in such manner as to draw the core 6 downwardly and depress the lever 4 against the action of spring 5 in such manner as to decrease the pressure upon the carbon pile 3 and increase the resistance thereof, so as to thus prevent the generator from delivering a greater current. I also adjust

the spring 22 in such manner that when the maximum charging voltage desired to have impressed across the storage battery 8 is reached, the coil 25 will cause core 24 to be drawn downwardly so as to depress the lever 21 and compress carbon pile 14 so as to reduce the resistance thereof, and thus cause the solenoid 12 to increase the resistance 3 and prevent the generator voltage 10 from rising above this predetermined limit. Therefore, the generator will at all times be governed in such manner that it cannot exceed its predetermined maximum current output, and if after supplying this current 15 to line the storage battery become charged until its voltage shall rise until the voltage across the same necessary to force the charging current therethrough, shall reach the maximum voltage for which the spring 22 20 is adjusted, the solenoid 25 will operate lever 21 as above described and prevent this voltage from being exceeded. Thus the battery will then be charged on a constant potential circuit and the current supply there- 25 to will gradually taper off to practically zero as the battery voltage approaches the voltage held constant by the coil 25, and while the batteries are thus being charged at a constant potential, the generator will 30 be protected against overload from any cause, by coil 11 in series therewith.

I do not wish in any way to limit myself to the exact details of construction or mode of operation set forth in this drawing and 35 specification, as I have merely shown and described a diagrammatic representation of one type of system embodying my invention, and it is obvious a wide departure therefrom may be made without departing 40 from the scope of said invention which is set forth in the following claims.

I claim—

1. Means for regulating a generator comprehending regulating means, a coil for operating the same, means for controlling the current in said coil and means for operating said controlling means operated by current fluctuations and operated by voltage fluctuations.

2. Means for regulating a generator comprehending a regulating element, a coil for governing the same, means for controlling the current in said coil comprising a current governing element and means for affecting said element comprehending a current operated magnet in circuit with the generator and means for affecting the said element comprising a voltage operated magnet in the circuit of the generator.

3. Means for regulating a generator; comprehending a regulating element, a coil for operating the same, means for controlling the current in said coil comprehending a re-

sistance varying element and means responsive to current fluctuations for operating the 65 said resistance element and means responsive to voltage fluctuations for controlling the resistance thereof.

4. Means for regulating a generator, comprehending a regulating means, electro-magnetic means for controlling the same actuated by a coil, means for controlling the current in said coil comprehending a resistance varying element and means for operating the same affected by the current output of the 75 generator, and means affected by the voltage of the generator for controlling the resistance thereof.

5. Means for regulating a generator comprehending means for controlling the magnetization thereof, a coil for operating said means and means for governing the current in said coil comprehending a resistance element and means responsive to current fluctuations for operating the same and means responsive to voltage fluctuations for affecting the same.

6. The combination with a generator of means for governing the same, electro-magnetic means for controlling said governing means, a resistance element for governing the controlling means, a current coil and means whereby the same varies said resistance element, a voltage coil and means whereby the same controls the resistance of said element.

7. The combination with a generator of means for governing the same comprehending a governing element, means for controlling the same, comprising an actuating coil and means for controlling the current in said coil comprehending current controlling means and means for operating the same comprising a coil in series with the generator and means for affecting the same comprising the coil in shunt to the generator.

8. Means for regulating a generator comprehending a regulating element, means for operating the same, means for controlling said operating means, means for operating said controlling means responsive to current fluctuations and means for operating said controlling means affected by voltage fluctuations.

9. Means for regulating a generator comprehending a regulating element, means for operating the same, means for controlling said operating means, means for operating said controlling means responsive to current fluctuations and means for affecting said controlling means responsive to voltage fluctuations.

JOHN L. CREVELING.
